US00D816769S

(12) **United States Design Patent** (10) **Patent No.:** **US D816,769 S**
(45) **Date of Patent:** **** May 1, 2018**

(54) **WRITING IMPLEMENT**

(71) Applicant: **MAPED**, Argonay (FR)

(72) Inventors: **Christophe Rimoux**, Villy-le-Pelloux (FR); **Daniel Racamier**, La Balme-de-Sillingy (FR)

(73) Assignee: **MAPED**, Argonay (FR)

(**) Term: **15 Years**

(21) Appl. No.: **29/588,421**

(22) Filed: **Dec. 20, 2016**

Related U.S. Application Data

(62) Division of application No. 35/500,208, filed on Oct. 1, 2015 (U.S. filing date under 35 U.S.C. 384), and having an international filing date of Oct. 1, 2015, now Pat. No. Des. 780,266.

(57) **CLAIM**

The ornamental design for writing implement, as shown and described.

DESCRIPTION

FIG. 1 is a front perspective view of a writing implement, showing our new design;

FIG. 2 is a front elevation view thereof;

FIG. 3 is a rear elevation view thereof;

FIG. 4 is a first side elevation view thereof; and,

FIG. 5 is a second side elevation view thereof.

Portions shown in broken lines form no part of the claimed design.

1 Claim, 5 Drawing Sheets
